UNITED STATES PATENT OFFICE.

PHILIP NICOLLE, OF TORONTO, CANADA.

SAFE.

SPECIFICATION forming part of Letters Patent No. 671,424, dated April 2, 1901.

Application filed July 7, 1900. Serial No. 22,814. (No model.)

To all whom it may concern:

Be it known that I, PHILIP NICOLLE, a subject of Her Majesty the Queen of Great Britain, residing in the city of Toronto, county of 5 York, and Province of Ontario, Canada, have invented certain new and useful Improvements in Burglar-Proof Bank-Safe Receptacles, (for which I have applied for a patent in Canada, filed December 7, 1899, Serial No. 10 88,224,) of which the following is a specification.

My invention relates particularly to improvements in a burglar-proof receptacle for bank-safes; and it consists of a number 15 of metal cases inserted one within the other and having suitable surrounding air-spaces between the walls of said cases and the inner case of said case, adapted for the reception of the bank-safe. Between the walls 20 of said cases and within the surrounding air-space of (preferably) the inner case is a gas-case encompassing the inner case, with the exception of the top. Illuminating or other gas is supplied to the gas-case in the ordinary 25 way and intercepted by a meter which is located in a convenient and conspicuous place, preferably in the manager's office. The object of the meter is to indicate an escape of gas from the gas-case caused by a rupture in 30 the same, and in addition to which is a sound-conduit connecting the space containing the gas-case with the manager's office. Through this the escaping gas will pass and be detected by the odor. Furthermore, any noise made 35 by operating on or within the cases will be readily detected by applying the ear to the same.

The bank-safe receptacle is located, preferably, in the corner of the bank building 40 formed by the angle of the walls facing on the public thoroughfare and incased in heavy masonry below the bank-floor. An apartment above the bank-safe receptacle and on a level with the bank-floor is isolated from 45 the bank by walls supported on the afore-said masonry and has but one entrance, opening into the manager's office.

The walls of the apartment—that is, above 50 the bank-safe receptacle—facing on the public thoroughfare contain large plate-glass windows, thereby permitting the public to have

a full view of the interior, and to further draw attention one of the opposite walls of the interior contains a large mirror and also a timepiece or any other suitable attraction. 55 The floor of the apartment is formed by the top plate or cover of the bank-safe receptacle. In the center is an opening corresponding in size to the inner case and adapted for the reception of the bank-safe. The safe employed may be similar to an ordinary safe with one exception and may or may not be burglar-proof. The false or enlarged top is slightly greater in superficial area than the opening in the case or receptacle into which 60 the safe is inserted, extending over the angular recess of the inner periphery of the opening in the top plate and entering the said recess, sinking flush with the top plate when down and in place. Sliding bolts located in 65 the upper portion of the receptacle support the safe when elevated, while vertical guides support the safe when in motion.

To raise and lower the safe, I employ a cable running over sheave-pulleys supported 75 on a beam located in the upper part of the apartment and terminating, preferably, in the basement of the bank building and connected with a winding-drum actuated by any suitable motive power. The ends of the cable, preferably the branches connecting with the safe, are so constructed as to be readily 80 detached when not in use, permitting of conveniently removing the same.

During banking hours the safe is in its 85 elevated position, when access to the interior can be had, and after banking hours the safe is lowered within the receptacle, and thereby proof against access to the interior. The apartment above the safe is illuminated, as 90 is customary, after banking hours. In this instance the illuminant is placed upon the top of the safe for the purpose of illuminating an attractive sign containing something descriptive and of public interest.

Figure 1 is a central cross-sectional view of my improved burglar-proof bank-safe receptacle on the line A to B of the following figure. Fig. 2 is a plan view in partial section. Fig. 3 is a plan view of the interior of the 95 bank building, showing the location of the bank-safe receptacle and arrangement of the 100

office, apartment, &c.; and Fig. 4 is a diminutive view showing the means employed to raise and lower the safe.

The material used in constructing the bank-safe receptacle is similar to that used in constructing vaults, safes, &c., and the manner of forming the several parts is also similar in as far as the design will permit. When located in the corner of the bank building 5 formed by the angle of the walls W^2 , as shown in Fig. 3, it is only necessary to construct walls W on the two remaining sides of the outer case A, including a suitable foundation A' , to inclose all but the top of the same 10 within masonry. Upon the walls W are constructed the walls N^3 , which isolate from and form an apartment in the bank building above the receptacle and has but one entrance, which opens into the manager's office E and 15 is closed by an iron-protected door d , in which and at a convenient height is a small window d' for the purpose of inspecting the interior when the door is closed. The portions of the walls W^2 which inclose the apartment 20 N^4 contain large windows O^2 , the sill O^3 of which is as near the sidewalk O^4 as is consistent with safety. Opposite one of the windows O^2 and on the interior of one of the apartment-walls N^3 is a mirror N^5 and also a 25 timepiece N^6 , which may be on either of the opposite walls N^3 .

Within the outer case A and surrounded by the air-space A^2 is the intermediate case D, resting on chairs B at its base and supported at the top by T-shaped guides C, secured to the outer case A, and guides D', secured to the case D. The object of the guides and chairs is to allow of the case D being inserted within the case A and supported 30 therein.

Within the intermediate case D and surrounding the inner case G, with the exception of the top, is the gas-case F, for the purpose hereinbefore described. Connecting the air-space containing the gas-case F with the exterior is the sound-conduit P, which terminates, preferably, in the manager's office. In the portion of the sound-conduit P that passes through the air-space A^2 there is an opening 45 PP on the under side, connecting also the said air-space with the exterior. The gas-supply pipe QQ connecting with the gas-case F, passes, preferably, through the conduit P, as shown.

To support the inner case G and maintain the desired air-space on either side of the gas-case F, spacing-pieces G^2 and G^3 , located, preferably, in the lower corners, are used, and that portion G^4 of the gas-case F covered by 50 the said spacing-pieces is formed solid, as shown.

Resting on the top of the three cases A, D, and G and held secure by bolts is the top plate N, and to further insure against removing the same double angle-iron N^2 is secured to the periphery of the top plate N and built within masonry. In the center is the open-

ing adapted for the reception of the bank-safe H and corresponding in size to the interior of the inner case.

Secured to the interior walls of the inner case G are vertical guides R', and secured to the sides of the safe H are corresponding guide-pieces R for the purpose of supporting the safe vertically. To receive the safe when down 70 and somewhat cushion and prevent the same coming in contact with the bottom of the inner case G, wooden supports G' are interposed, as shown, and to support the safe when up—that is, when access to the interior can be had—75 sliding bolts S, located in the top plate N, are forced forward by inserting a lever in the slot V and fulcrumed in the opening T of the top plate N. Secured to the sides of the safe H are catches R², which rest on the bolts S when 80 the latter are forced forward and support the safe H in its elevated position. To prevent the bolts S from moving from under the catches R², a downwardly-projecting portion of the latter enters a corresponding recess in the former. 85

The enlarged or false top of the safe H is greater in superficial area than the opening into which it enters—namely, the inner case. The projecting portion K' of the enlarged top 95 enters the angular recess K² of the top plate N, sinking flush with the same, and thereby preventing all access to the interior when the safe is down.

The means employed to raise and lower the 100 safe H consist of a cable H³, operating over sheave-pulleys H⁴ and H⁵, supported in a beam or iron girder K in the upper part of the apartment, having one end secured to a winding-drum H⁶, located, preferably, in the 105 basement of the building and actuated by some suitable motive power and the opposite end terminating in branches H² and secured by hooks to the fixed eyes H' on the top of the safe H.

Having described my invention, what I 110 claim as new, and desire to secure by Letters Patent, is—

1. In a burglar-proof bank-safe receptacle, the combination with a plurality of cases one 115 within the other and separated by intervening air-spaces inclosed by a top common to all, of a gas-case contained within the intervening air-space adjacent to and encompassing the inner case, the intervening air-space 120 surrounding said gas-case communicative with the exterior, and the inner case of said receptacle adapted for the ingress and egress of the bank-safe, substantially for the purpose hereinbefore set forth.

2. In a burglar-proof bank-safe receptacle, the combination, with a plurality of cases one 125 within the other and separated by intervening air-spaces inclosed by a top secured to said cases, of a gas-case inclosed by said cases and surrounding the inner case of said cases with the exception of the top, a sound-conduit connecting the air-space containing the 130 said gas-case with the exterior, the inner case

of said cases adapted for the reception of the bank-safe, and means for raising and lowering said safe, substantially as shown and described.

- 5 3. In a burglar-proof bank-safe receptacle, the combination of a plurality of cases inclosed within the outer case of said cases and separated by intervening air-spaces, a top secured to said cases and inclosing said air-
10 spaces, a gas-case contained in the air-space surrounding the inner case of said cases and encompassing the said inner case with the exception of the top, a sound-conduit connecting the air-space containing said gas-case

with the exterior, an opening into said conduit connecting the air-space inclosed by the said outer case with the exterior, the inner case adapted for the reception of the bank-safe, said bank-safe adapted to be raised and lowered within said receptacle, and means 20 for supporting said safe when elevated, substantially as and for the purpose hereinbefore set forth.

PHILIP NICOLLE.
